UNITED STATES PATENT OFFICE.

GRANVILLE E. PALMER, OF BROOKLINE, AND ERNEST G. JOHANSSON, OF BOSTON, MASSACHUSETTS, ASSIGNEES, BY MESNE ASSIGNMENTS, TO THE PALMER ELECTRIC AND MANUFACTURING COMPANY, OF WALTHAM, MASSACHUSETTS, A CORPORATION OF MASSACHUSETTS.

SWITCH BOX.

Application filed June 30, 1925. Serial No. 40,645.

This invention pertains to switch boxes of the type commonly used for enclosing the switch which controls the admission of electrical current from a power main to the premises of a purchaser of current, the switch being interposed between the power main and a meter which measures the current delivered. Switch boxes of this type are usually made of metal and adapted to be sealed or locked to prevent unscrupulous persons from surreptitiously diverting current from the main at a point in advance of the meter. In order to protect the conducting wires intermediate the switch box and meter, the latter is commonly mounted in fixed relation to the switch box and the terminal casing of the meter and the end wall of the box are provided with interfitting parts or connected by means of a rigid metallic conduit thereby providing an armored passage for the conducting wires leading from the switch to the meter.

Since electric meters of different makes and capacities have differently shaped terminal casings it has been proposed heretofore to provide the switch box with removable and interchangeable end walls having different sized openings or sockets adapted to cooperate with the different styles and sizes of meter casing and since, under some circumstances, as, for example before the connection of the meter to the box, it is desirable completely to close the end of the box, imperforate end walls have also been provided.

While such removable and interchangeable end walls are to a certain extent useful they have the great disadvantage that they are easily lost or misplaced. The danger of loss may readily be appreciated from the fact that the switch box is usually installed by one set of workmen who leave the box in place but unsealed and with the electrical circuits inoperative. At some subsequent time the box and its conductors are inspected by representatives of bureaus having jurisdiction in such matters and after inspection the box may remain for a very considerable period before another set of workmen come to install the meter, make the circuit connections, and seal the box and meter cases.

The fact that several groups of workmen

deal with the switch box at various times and often with considerable periods of time intervening is conducive to misplacement or loss of end walls of removable, interchangeable type. As above pointed out it is quite desirable completely to close the end wall of the box before the installation of the meter as the switch box is often installed during the early stages of building construction and dirt, plaster, whitewash, etc., may, unless the box be completely covered, drop into the latter and foul the switch parts. Thus it is often the case that the application of the closure member or interchangeable end wall is neglected and the switch may be found to be in bad condition when the workmen arrive to install the meter while the loss or misplacement of the proper end wall may greatly delay installation of the meter.

In accordance with the present invention we have provided a switch box having an end wall adapted to serve either as a complete closure for the box, or when associated with a meter, to provide the necessary passage or wire-way, such end wall being of the type adapted to support meters of any of the usual standard styles, and we have so connected this improved end wall with the box that while movable relatively to the box in accordance with the conditions which it is adapted to meet, it is not detachable or removable from the box and therefore cannot be lost or misplaced during the period which elapses between the setting of the box and installation of the meter.

Usually the meter is mounted upon or in contact with the upper end wall of the switch box although it may be arranged adjacent to or against the bottom of the box and while for convenience in description we herein illustrate our present invention as embodied in the upper end wall of the box we contemplate that it may be applied with equal advantage to other walls of the box and do not wish to limit ourselves as to the particular wall of the box to which the invention may be applied.

In the accompanying drawings in which a preferred embodiment of the invention is illustrated by way of example,

Fig. 1 is a front elevation of our improved switch box showing its door closed but partly broken away, and its movable end wall arranged to cooperate with an electric meter of one usual type;

Fig. 2 is a similar front elevation showing the upper part only of the box with its end wall disposed as in Fig. 1; but showing a meter of another type associated therewith;

Fig. 3 is a view similar to Fig. 2, but showing a still further form of meter;

Fig. 4 is a fragmentary front elevation of the upper part of the box, the door being open, showing the movable end wall of the box reversed relatively to its position as indicated in the preceding figures and having associated therewith a meter of another form;

Fig. 5 is a plan view of the box to larger scale, with its door closed and with the movable end wall positioned for the accommodation of meters such as shown in Figs. 1 to 3 inclusive.

Fig. 6 is a side elevation of the end wall as it appears before application to the box and in vertical position;

Fig. 7 is a fragmentary section on the line 7—7 of Fig. 5;

Fig. 8 is a plan view of the improved switch box to smaller scale showing the cover closed and the end wall disposed as in Fig. 4, the wire conduits being shown in section;

Fig. 9 is a plan view of a removable cover plate for closing an aperture in the end wall;

Fig. 10 is a fragmentary cross section to larger scale on the line 10—10 of Fig. 5;

Fig. 11 is a fragmentary elevation of the upper part of the left hand side wall of the box, viewed from the inside;

Fig. 12 is a horizontal section substantially on the line 12—12 of Fig. 11;

Fig. 13 is a perspective view of the upper part of the box showing the cover open and the end wall positioned as in Figs. 1, 2 and 3;

Fig. 14 is a similar perspective view showing the cover wide open and the end wall drawn forwardly and partially swung up as it appears when it is being reversed; and

Fig. 15 is a perspective view of the upper part of the box showing the end wall fully reversed as respects the position shown in Fig. 13 and with the cover partly closed.

Referring to the drawings, the switch box, which is preferably made of sheet metal, comprises the rear wall 1, the vertical side walls 2 and 3, the bottom end wall 4, the top end wall 6 and the door or cover 5. Preferably this cover is hinged to one of the side walls, for example, the wall 2 and is provided with an aperture 6' normally closed by a slide 7 which gives access to the fuse disposed within the box. A suitable handle 8 is arranged at the right hand side of the box. This handle controls the switch within the box and also constitutes a lock for the slide 7 which covers

the fuse aperture 6' when the switch is in circuit closing position. The cover is furnished with suitable means, not shown, by which it may be locked or sealed in the usual manner.

The rear wall 1 of the box is furnished with openings for the reception of screws 11 by means of which it is attached in operative position against a suitable supporting member, for example a wall, and is also furnished with openings for the reception of other screws 12 by means of which a meter supporting plate 13, shown in broken lines, may be attached to the rear wall of the box. These screws 12 may also extend into the supporting member and the plate 13 is provided with openings for screws 14 which also extend into the wall. The plate 13 is provided with suitable retaining devices, for example, bolts 15 by means of which a meter M, indicated in broken lines, may be secured to the front face of the plate 13.

In accordance with the present invention the top end wall 6 of the box is adjustable with respect to the body of the box. This end wall comprises a plate 16 (Figs. 5, 6, 7 and 12) having flanges 17 and 18 respectively at its right hand and left hand edges and also a flange 19 extending along one of its transverse edges. The flanges 17 and 18 are furnished with elongate slots 20 (Fig. 6) extending from front to rear and such slots terminating at their opposite ends in circular openings 20^a and 20^b so that each slot is in effect a double key hole slot.

The end wall 6 is pivotally connected to the body of the box by means of a pair of aligned pivot members 21 disposed near the upper forward corners of the side walls 2 and 3 respectively. These pivot members preferably take the form of rivets having shank portions which extend through openings in the walls 2 and 3 respectively and having heads 22 at the outer surfaces of the side walls of the box. These rivets also have horizontal flat heads 23 at the inner sides of the box walls, such flat heads being of a vertical thickness slightly less than the width of the slots 20, so that they may slide freely relatively to such slots, and having a front to rear width slightly less than the diameter of the openings 20^a and 20^b. If desired these heads 23 may project inwardly beyond the inner surfaces of the flanges 17 and 18 of the end wall and at their inner ends may have tongues 24 directed substantially at right angles to their flat heads.

The flat head 23 of each rivet 21 is normally disposed in one of the circular openings at the end of the corresponding slot 20 and when in this position the end wall may be swung about the axis defined by the rivets 21. When the end wall occupies a horizontal position it may be drawn forwardly, the flat head 23 of each rivet sliding along the narrow slot 20 of the corresponding flange until the head of the rivet enters the other circular opening where-

upon the end wall may be swung about the axis defined by the rivets. One of the openings, for example the opening 20^b, may be dispensed with if desired, although it is more 5 convenient to have both openings. When the end wall is properly positioned, whether with one or the other side up, its rear edge is supported upon suitable brackets 22^a projecting from the rear wall 1 of the box.

- 10 That edge of the plate 16 which is opposite to the flange 19 is provided with an inwardly extending recess R which forms a suitable passage or wire-way for the conductors leading from the interior of the box to a meter 15 mounted above the box. As here shown this recess is a substantially rectangular formation. Bordering this recess but spaced from the edge thereof are angle bars each comprising a flange 25 secured by rivets to the face 20 of the plate 16 and a flange 27 at right angles to the flange 25 and preferably integral therewith. The flanges 27 project from the same face of the plate 16 as the flanges 17, 18 and 19 and support a shelf member 28 spaced from 25 the surface of the plate 16 and having flanges 29 which are secured to the flanges 27 by rivets 30.

The end portions of the shelf 28 are relatively wide and overhang that part of the 30 plate 16 which is intermediate the edge of the recess R and the flange 27, but that portion of the shelf which extends along the transverse part of the flange 27 is cut away so as to leave a relatively narrow portion 30' which exposes 35 a part 31 of the underlying plate 16. The transversely extending part 27' which may be integral with and extend between the flange 27 is provided with a shallow recess 32 to accommodate meters of certain type as hereafter referred to.

The recess R extends inwardly as above described from one of the transverse edges of the end wall 6 and preferably terminates short of the front to rear center of the end 45 wall. At that portion of the plate 16 intermediate the flange 27' and the flange 19 an opening 33, preferably circular, is provided which is normally covered by a plate 34 (Fig. 9) removably secured in position in any desired manner, as for example, by providing it with ears 35 projecting through the opening and having apertures for the reception of the ends of a pin 36 whose ends overlie the edges of the opening 33. This plate is preferably 50 positioned at the side of the end wall 6 opposite to that to which the flanges 25 are secured so that the side 37 of the end wall is relatively smooth and free from projections.

Referring to Fig. 1, a meter M is shown in 60 broken lines as mounted upon the upper end wall of the box, the end wall occupying the position indicated in Fig. 13. This meter M is provided with a downwardly extending terminal casing 38 having supports 39 which 65 rest upon the shelf 28 and support the meter

in position, the downwardly projecting tongue 40 of the meter casing being situated in the recess 32 of the flange 27. With the parts thus positioned the conductors which extend up from the box through the recess R 70 into the casing of the meter are fully protected throughout their entire length so that it is impossible to tamper with them for the purpose of stealing electric current.

In Fig. 2 the meter M^a is provided with a downwardly projecting conduit casing 40' which fits snugly in the socket provided by the flange 27. In Fig. 3 the meter M^b has a downwardly projecting conduit casing 41 which fits within the space defined by the 80 inner edge of the shelf 28. The end wall of the box is thus adapted when made in the manner above described to accommodate meters of various standard types when the end wall is arranged as shown in Fig. 13.

In Fig. 4 a meter M^c is shown associated with the box, such meter being connected to the box by means of a metallic conduit 42. To adapt the box for association with this type of meter the box cover is first opened and the end wall 6 is drawn forwardly until the rivets 23 are disposed in the openings 21 in the flanges 17 and 18, whereupon the forward edge of the end wall is swung upwardly as indicated in Fig. 14 about the axis defined by the rivets and then swung rearwardly and downwardly into horizontal position as shown in Fig. 15. The pin 36 being removed, the cover 34 is taken off and the end of the conduit 42 is secured in the opening as for example by means of clamping nuts 43 and 44 (Fig. 4).

The door or cover 5 of the box is furnished with marginal flanges 9 at its lower and vertical edges, and at its top edge with a flange 10, which is substantially wider than the flanges 9 and adapted, when the end wall member occupies the position indicated in Fig. 15, to close the recess R. Thus when the end wall is positioned for association with a meter such as shown in Fig. 4 the recess R is closed whenever the box cover is closed without necessitating the provision of a separate closure element which might easily be lost or misplaced.

The slots 20 permit the end wall 6 as an entirety to be moved bodily forward out of its normal position in engagement with the back wall while positively and permanently connected with the side walls. After the end wall has been moved outwardly it can be swung downwardly into a vertical position so as to not interfere with the workmen installing the meter. These movements, when the meter is installed, makes the lower end of the meter terminal casing more accessible.

Prior to installation of the meter, the end wall of the box is also arranged in the position shown in Fig. 15, the cover 34 being still attached to the end wall so that it completely

closes the opening 33. When the box cover 5 is closed the end wall of the box presents an imperforate surface so that it is not possible for plaster, dirt or other substances to enter the box and foul the switch and its connections.

The end wall thus provided furnishes a temporary and complete closure for the end of the box prior to installation of the meter and although this end wall is permanently secured to the box and cannot be removed therefrom, it is adapted by moving it as above described for association with meters of widely different types such as are commonly met with in the trade.

When it is known that the box will only be used with a meter of the general type shown in Fig. 4, the recess R and the flange 27 may be omitted, and the cover plate 34 for the opening 33 may also be omitted since by properly positioning the end wall the opening 33 will be covered by the flange 10 of the door 5 when the latter is closed, thus affording a complete closure for the box prior to the attachment of the meter.

While the end wall has herein been shown as the upper end wall of the box, it is contemplated that it may as well constitute the lower end wall of the box or that both of such end walls may be made in similar fashion, if desired. It is further contemplated that various changes in detail of construction as well as in proportions of parts employed and meter used in constructing them may be made without departing from the spirit of the invention. We do not wish to be limited, therefore, except by the scope of the appended claims.

We claim:

1. A switch box comprising side walls, a reversible end wall member having an opening extending inwardly from one edge and pivotally supported between said side walls and partially closing the end of the box, and a cover for the box, the cover having a part which covers said opening when the cover is closed and the end wall is in one of its positions.

2. A switch box comprising side walls, a reversible end wall member pivoted upon supports carried by the side walls, said end wall member having an opening therein extending inwardly from one edge thereof, a cover for the box, and a flange projecting from the cover which closes the opening in said end wall member when the cover is closed and said opening is adjacent the front of the box.

3. A switch box comprising side walls and an end wall, said end wall having openings of different contour therethrough disposed respectively in and adjacent to its opposite transverse edges, said end wall being pivotally connected to the box and reversible to permit either of said openings to be properly positioned to receive the conductors from an

electric meter associated with the box, and means for closing both of said openings when the box is not connected to a meter, one of said means comprising a cover having a flange covering said edge opening when adjacent to the front of the box.

4. A switch box comprising spaced relatively fixed side walls, a reversible end wall, said end wall having flanges parallel to the respective side walls, each flange having an opening therein, and a fixed pivot member projecting from each side wall of the box into the opening in the adjacent flange of the end wall thereby defining a pivotal axis about which the end wall may swing, said end wall having a conductor opening extending inwardly from one edge and said cover having a flange covering said conductor opening when it is at the front of said box.

5. A switch box comprising spaced relatively fixed side walls and a reversible end wall, the latter having flanges parallel respectively to the opposite side walls, each flange having an elongate, front to rear slot, a fixed pivot member projecting inwardly from each side wall into the slot in the adjacent flange, the end wall turning freely upon said pivot pins as an axis, the pins and slots also permitting the end wall to slide from front to rear, said wall having an opening extending inwardly from one edge thereof, and a cover having a flange covering said opening when said edge is at the front of the box.

6. A switch box comprising spaced relatively fixed side walls and a reversible end wall, the end wall having flanges disposed respectively adjacent to the inner surfaces of the opposite side walls, each flange having an elongate narrow slot extending from front to rear, each slot terminating at one end at least in a circular opening of a diameter greater than the width of the slot, a fixed pivot member projecting inwardly from each side wall, each pivot member having a flat head adapted to enter the narrow part of the slot in the adjacent flange and to constitute a guide for the end wall as the latter is slid forwardly or rearwardly, said flat heads when positioned in the circular enlargements at the ends of the slot constituting pivots about which the end wall may freely swing, said end wall having an opening extending inwardly from one edge and a cover having a flange covering said opening when said edge is adjacent to the front of the box.

7. A switch box comprising side walls and an end wall having an opening extending inwardly from one edge, said end wall having flange members embracing the axis of said opening and projecting from one of its sides, said flange members having surfaces of different contour being shaped to interfit with the terminal casings of electric meters of different styles, said end wall being reversible to permit its flanged side to be turned to the

- inside of the box, and means to prevent removal of said end wall from the box and a cover having a flange closing said opening when adjacent to the front of the box.
5. A switch box comprising side walls and an end wall having an opening extending inwardly from one edge, said end wall being provided upon one side with projecting members embracing the axis of said opening and having surfaces of different contour each interfitting with the terminal casing of an electric meter, the other side of the end wall being substantially smooth, the end wall being reversible to expose either of its sides to the exterior of the box, and means preventing removal of the end wall from the box and a cover having a flange closing said opening when adjacent to the front of the box.
6. A switch box comprising side walls and an end wall, the end wall having an opening extending inwardly from one edge and a member projecting from one of its faces forming a socket for the reception of the terminal casing of an electric meter, said socket embracing the axis of said opening, said end wall having a second opening therethrough between the inner margin of the socket and the edge of the wall remote from the socket, said opening being adapted to receive a conductor conduit leading to a meter of another type, the end wall being pivoted and reversible to expose either side to the exterior whereby to position either the socket or said opening to cooperate with a meter, a seal for said opening and a cover for said box, having a flange closing the second opening when adjacent to the front of the box.
7. A switch box having an end wall with an opening extending inwardly from one of its edges, flanges projecting from one side of the end wall substantially at right angles to the plane thereof, and other flanges substantially parallel to the surface of said end wall but spaced therefrom, the several flanges respectively embracing the axis of said opening and defining sockets of different contour adapted to receive the terminal casings of electric meters of different size and contour.
8. A switch box having side walls and an end wall, the end wall having a recess or opening extending inwardly from one of its transverse edges, an upwardly projecting flange bordering but spaced from the edge of said recess, said flange defining a socket for the reception of the terminal casing of an electric meter, and pivot means connecting the end wall to the side walls and permitting that side of the end wall having the projecting flange to be turned inwardly or outwardly and a cover having a flange adapted to close said opening when said projecting flange is turned inward.
9. A switch box having side walls and an end wall, the end wall having a recess or opening extending inwardly from one of its transverse edges, an upwardly projecting flange bordering but spaced from the edge of said recess, a shelf projecting from the inner surface of said flange, the shelf being parallel to and overlying that part of the end wall between the flange and the edge of the recess, said flange being narrow at certain parts to expose said underlying portion of the end wall, the contours of the flange and the inner edge of the shelf being different and corresponding to the shape of the terminal casings of electric meters of different styles.
10. A switch box having side walls and an end wall, the end wall being reversible and having a recess or opening extending inwardly from one of its transverse edges, an upwardly projecting flange bordering but spaced from the edge of said recess, a shelf projecting from the inner surface of said flange, the shelf being parallel to and overlying that part of the end wall between the flange and the edge of the recess, said flange being narrow at certain parts to expose said underlying portion of the end wall, the flange and shelf cooperating to form sockets of different contour for electric meters of different styles, and pivot means connecting the end wall to the box and permitting the end wall to be reversed to expose said sockets at the outside of the box or alternatively to dispose them inside of the box and a cover having a flange closing said opening when said flanges are within said box.
11. A switch box having side walls and an end wall, the end wall having a recess or opening extending inwardly from one of its transverse edges, an upwardly projecting flange bordering but spaced from the edge of said recess, said end wall being pivotally supported so that it may be turned to bring its recessed edge at the front of the box with the bordering flange inside of the box, and means for closing said recess or opening when the end wall is so positioned.
12. A switch box having side walls and an end wall, the end wall having a recess or opening extending inwardly from one of its transverse edges, an upwardly projecting flange bordering but spaced from the edge of said recess, said end wall being pivotally supported so that it may be turned to bring its recessed edge at the front of the box with the bordering flange inside of the box, and a cover for the box, said cover having a flange adapted to cover said recess or opening when the end wall is so positioned and the cover is closed.
13. A switch box having side walls and an end wall, the end wall having a recess or opening extending inwardly from one of its transverse edges, an upwardly projecting flange bordering but spaced from the edge of said recess, the opposite side of the end wall being substantially smooth, means pivotally supporting the end wall so that either its

flanged surface or its smooth surface may be turned inwardly, and a hinged cover for the box having an inwardly turned marginal flange, said flange overlapping the front edge 5 of the end wall when the cover is closed and concealing said recess when the smooth side of the end wall is turned outwardly.

17. In an electric meter protecting cabinet adapted for enclosing a current controlling 10 appliance, the combination with the back and side walls of the cabinet, of an end wall constructed for protective association with an electric meter normally positioned perpendicularly to the said back and side walls so 15 as to substantially close the cabinet at one end, and means for positively and permanently connecting the said end wall with both of the side walls, the said means permitting the end wall as an entirety to be moved out of 20 its normal position in engagement with the said back wall, while positively and permanently connected with the said side walls as aforesaid.

18. In an electric meter protecting cabinet 25 adapted for enclosing a current controlling appliance, the combination with the back and side walls of the cabinet, of an end wall constructed for protective association with an electric meter and normally positioned perpendicularly to the said back and side walls 30 so as to substantially close the cabinet at one end, and means for positively and permanently connecting the said end wall with both of the said side walls so as to permit the end wall 35 to be moved bodily forward and then angu-

larly about a transverse horizontal axis while remaining so connected.

19. In an electric meter protecting cabinet 40 adapted for enclosing a current controlling appliance, the combination with the back and side walls of the cabinet, of an end wall constructed for protective association with an electric meter normally positioned perpendicularly to the said back and side walls so as to substantially close the cabinet at one end, 45 and means for positively and permanently connecting the said end wall with both of the side walls, the said means permitting the end wall as an entirety to be moved out of its normal position in engagement with the 50 said back wall, while positively and permanently connected with the said side walls as aforesaid, to facilitate the installation of the meter.

20. A switch box comprising side walls and 55 an end wall, said end wall having a pair of openings of different contour disposed respectively, one in one of its transverse edges and the other adjacent to the opposite edge, said end wall being pivotally supported to permit 60 it to be reversed, a seal for said second opening, positioning means for the seal accessible from one side only of the end wall, and a cover having a flange which normally covers the first of said openings when it is adjacent 65 to said cover.

Signed by us at Cambridge, Massachusetts,
